UNITED STATES PATENT OFFICE.

GEORGE M. SHEFFER, OF EMLTON, PENNSYLVANIA.

RAIL-JOINT.

No. 926,215.

Specification of Letters Patent. Patented June 29, 1909.

Application filed March 18, 1909. Serial No. 484,154.

To all whom it may concern:

Be it known that I, GEORGE M. SHEFFER, a citizen of the United States, residing at Emlton, in the county of Venango, State of Pennsylvania, have invented certain new and useful Improvements in Rail-Joints; and I hereby declare the following to be a full, clear, and exact description of the invention, such as will enable others skilled in the art to which it appertains to make and use the same.

This invention relates to railroad construction and has special reference to a rail joint.

One object of the invention is to improve the general construction of rail joints.

A second object of the invention is to provide a rail joint which shall render it unnecessary to drill or punch the ends of rails for the reception of bolts.

20 A third object of the invention is to provide an improved rail joint having a mechanism arranged to force a pair of fish plates into strong frictional engagement with the web of a rail.

25 A fourth object of the invention is to provide an improved locking means for such a joint.

With the above and other objects in view the invention consists in general of a pair of 30 imperforate rail ends, a pair of improved fish plates, means for forcing the fish plates into strong frictional engagement with the webs of the rail ends and other means to lock the various parts in adjusted position on the rail 35 ends.

The invention further consists in certain novel details of construction and combinations of parts hereinafter fully described, illustrated in the accompanying drawings, 40 and specifically set forth in the claims.

In the accompanying drawings, like characters of reference indicate like parts in the several views, and:—Figure 1 is a top plan view of a rail joint constructed in accordance 45 with this invention. Fig. 2 is a side elevation thereof. Fig. 3 is a horizontal section of the line 3-3 of Fig. 2, certain of the parts being broken away. Fig. 4 is a transverse section through one of the rail ends showing the 50 joint in end elevation. Fig. 5 is an end view of the chair.

The reference characters A and B indicate in general the ends of a pair of rails each provided with a web 10, head 11 and base 12 and

these rails may be of any desired form or proportions as is best adapted for the specific use for which they are intended.

Between the ends of the rail sections is a chair comprising a centrally disposed distance block of the same contour as the head and web of the rail and this distance block is indicated by the numeral 13. This distance block is also provided with a spacer 14 of the same contour as the rail base and forming a continuation of the distance block 55 proper. Projecting from either end of the spacer 14 are rail base engaging members 15 which fit closely beneath the under side of the rail base and the lateral upper portions of said base, terminating in spaced relation 60 to the web of the rail. This construction is carried out between the two pocket members so that the exterior contour of the chair is uniform on its sides and base with the exception of notches 16 arranged in the base edges 70 for the reception of rail spikes. By means of this construction there is provided a pair of pockets or slots 17 of which, when the chair is in position on the rail ends the web faces 75 form the inside walls while the outside walls 80 are formed by the spaced sides of the chair.

Extending through each of the pockets or slots 17 is a fish-plate having one end portion 18 tapered toward its extremity throughout its length and adapted to fit closely against 85 the webs of the rails and distance block, and a longer wedge shaped end portion 19 provided with an inner surface adapted to fit closely against the web of a rail while the outer surface tapers in the direction of the 90 inner surface from the lug 20 to the point. The lug 20 is designed to receive blows when driving the fish-plate into or out of place. The fish-plates project for some distance on 95 each side of the chair and upon these projecting portions are held clamping members comprising a portion 21 forming a sliding fit on the outer parts of the rail base and a pair of upstanding portions 22 spaced slightly 100 farther apart than the distance between the outer faces of the point and butt of the respective ends of the fish-plates whereon they are engaged. The distance between the upstanding portions of the clamping members is, however, not sufficient to permit these 105 members being forced along said fish-plates more than about one-half the distance of the projecting portion. It will thus be noted

that as these clamps are forced along the fish-plates the latter will be drawn together into strong frictional engagement with the webs of the rails. In order to hold the 5 clamps from jarring loose each of these clamps is provided with a laterally projecting arm 23 having a pair of upstanding portions 24 provided with inwardly disposed, oppositely positioned ribs 25 and terminal 10 ears having oppositely disposed perforations 26. What is preferably termed the lock bar comprises a central portion 27 upon each side of which is an end 28 provided with pairs of spaced opposed ribs 29 adapted to fit 15 between the upstanding portions 24 and closely engage the rib 25. In order to hold this bar from rising out of its position pins 30 extend through the perforations 26 and these pins may be of any desired construction 20 such as cotter pins.

In the assembling of the device the rail ends are placed in the pockets of the chair after the clamping members have been slipped over said ends. The fish-plates are 25 then passed through the slots of the chair with their longer beveled end portions pointing in opposite directions and are driven on with the desired tightness to hold the rails firmly. The clamps are then forced over 30 the fish-plates until the latter strongly engage the webs of the rails when the locking bar is applied. The cotters are then inserted and the joint is ready for use.

There has thus been provided a single and 35 highly efficient device of the character described and for the purpose specified.

It is obvious that minor changes may be made in the form and proportions of this invention without departing from the material 40 principles thereof. It is not therefore desired to confine the invention to the exact form herein shown and described, but it is wished to include all such as properly come within the scope of the appended claims.

Having thus described the invention, what is claimed as new, is:—

1. In a rail joint, the combination with a pair of rail ends, of a pair of fish-plates each having a wedge shaped end, clamping members adapted to be forced over said fish-plates each provided with a laterally projecting arm having spaced upturned portions and a lock bar engaged over said portions and provided with spaced ribs to hold said 55 clamping members in position.

2. In a rail joint, the combination with a pair of imperforate rail ends, of a pair of imperforate fish-plates each having wedge shaped ends, clamping members adapted to be forced over said fish-plates each provided with a laterally projecting arm having spaced upturned portions and a lock bar engaged over said portions and provided with spaced ribs to hold said clamping members in position.

3. In a rail joint, the combination with a pair of butt ended rail ends, of a chair provided with rail end receiving pockets and a distance block to receive and hold said rail ends in spaced relation and having guide slots formed therethrough, of a pair of fish-plates each having a wedge shaped end each passing through one of said slots, clamping members adapted to be forced over said fish-plates, and means to hold said clamping 75 members in position.

4. In a rail joint, the combination with a pair of butt ended rail ends, of a chair provided with rail end receiving pockets and a distance block to receive and hold said rail 80 ends in spaced relation and having guide slots formed therethrough, of a pair of fish-plates each having a wedge shaped end each passing through one of said slots, said ends being positioned in opposite directions, 85 clamping members adapted to be driven over said fish-plates, and means to hold said clamping members in position.

5. In a rail joint, the combination with a pair of butt ended rail ends, of a chair provided with rail end receiving pockets and a distance block to receive and hold said rail ends in spaced relation and having guide slots formed therethrough, of a pair of fish-plates each having a wedge shaped end each 90 passing through one of said slots, clamping members adapted to be forced over said fish-plates each provided with a laterally projecting arm having spaced upturned portions and a lock bar engaged over said portions and provided with spaced ribs to hold 95 said clamping members in position.

6. In a rail joint, the combination with a pair of butt ended rail ends, of a chair provided with rail end receiving pockets and a 105 distance block to receive and hold said rail ends in spaced relation and having guide slots formed therethrough, of a pair of fish-plates each having a wedge shaped end each passing through one of said slots, clamping members adapted to be driven over said fish-plates each provided at its outer end with a pair of spaced upstanding members, and a lock bar provided at each end with pairs of 110 spaced opposed ribs adapted to engage over 115 said upstanding members to hold said clamping members in position.

7. In a rail joint, the combination with a pair of butt ended rail ends, of a chair provided with rail end receiving pockets and a 120 distance block to receive and hold said rail ends in spaced relation and having guide slots formed therethrough of a pair of fish-plates each having a wedge shaped end each passing through one of said slots, said ends 125 being positioned in opposite directions, clamping members adapted to be driven over said fish-plates each provided at its outer end with a pair of spaced upstanding members, and a lock bar provided at each 130

end with pairs of spaced opposed ribs adapted to engage over said upstanding members to hold said clamping members in position.

8. In a rail joint, the combination with a pair of imperforate butt ended rail ends, of a chair provided with rail end receiving pockets and a distance block to receive and hold said rail ends in spaced relation and having guide slots formed therethrough, of a pair of imperforate fish-plates each having a wedge shaped end each passing through one of said slots, clamping members adapted to be forced over said fish-plates, and means to hold said clamping members in position.

15 9. In a rail joint, the combination with a pair of imperforate butt ended rail ends, of a chair provided with rail end receiving pockets and a distance block to receive and hold said rail ends in spaced relation and having guide slots formed therethrough, of a pair of imperforate fish-plates each having a wedge shaped end each passing through one of said slots, said ends being positioned in opposite

directions, clamping members adapted to be driven over said fish-plates, and means to hold said clamping members in position.

10. In a rail joint, the combination with a pair of imperforate butt ended rail ends, of a chair provided with rail end receiving pockets and a distance block to receive and hold said rail ends in spaced relation and having guide slots formed therethrough, of a pair of imperforate fish-plates each having a wedge shaped end each passing through one of said slots, clamping members adapted to be forced over said fish-plates each provided with a laterally projecting arm having spaced upturned portions and a lock bar engaged over said portions and provided with spaced ribs to hold said clamping members in position.

In testimony whereof, I affix my signature, in presence of two witnesses.

GEORGE M. SHEFFER.
